UNITED STATES PATENT OFFICE.

IRA C. WILLIAMS, OF COLDWATER, MICHIGAN.

FLUID-HYDROCARBON BURNER.

1,175,493.

Specification of Letters Patent. Patented Mar. 14, 1916.

Application filed October 25, 1915. Serial No. 57,772.

To all whom it may concern:

Be it known that I, IRA C. WILLIAMS, a citizen of the United States, residing at Coldwater, in the county of Branch and State of Michigan, have invented a new and useful Fluid-Hydrocarbon Burner, of which the following is a specification.

The device forming the subject matter of this application is adapted to be employed for converting fluid fuel into gas and one object of the present invention is to provide novel means for mixing the gas with air and for effecting a combustion of the product thus brought about.

Another object of the invention is to improve the deflector structure.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 shows the invention in perspective; Fig. 2 is a vertical transverse section; Fig. 3 is a sectional detail, the cutting plane being passed through the headers and the pipes which connect the headers; Fig. 4 is a bottom plan of the cap which is carried by the deflector structure; Fig. 5 is a perspective view depicting an auxiliary element employed at times in initially heating certain parts of the structure.

In carrying out the present invention there is provided a deflector which is denoted generally by the numeral 1, the deflector being of cup-shape and embodying an upstanding rim 2. In the bottom 3 of the deflector 1 an opening is formed, the opening being surrounded by an upstanding flange 4 as clearly shown in Fig. 2. The deflector 1 is upheld by a plurality of multi-part, longitudinally extensible legs 5.

At one side of the deflector, the rim 2 thereof is cut away to define an opening and at the ends of this opening, the rim of the deflector is fashioned into angular, outstanding flanges 6 in which is journaled for rock-

ing movement a rod 7 having at its outer end a handle 8 of any desired sort. A movable deflector section 9 is secured to the rod 7 and is adapted to be moved toward and away from the body portion of the deflector, when the rod 7 is rocked.

The invention comprises a pair of headers denoted by the numerals 10 and 11 and shown in detail in Fig. 3. The headers 10 and 11 are equipped with openings 14 adapted to receive securing elements 12 whereby the headers may be attached to the flanges 6 of the deflector rim 2. The header 11 is provided with a longitudinal passage 15, one end of which is closed by a removable plug 16. The header 10 is provided with transverse passages 17 and 18. An upper pipe 19 is adapted to slide for expansion in the upper passage 17 of the header 10 and is secured to the header 11 and communicates with the longitudinal passage 15 in the header 11. A lower pipe 20 slides for expansion in the lower passage 18 in the header 10 and is secured to the header 11 and communicates with the longitudinal passage 15 of the header 11. The pipes 19 and 20 and the header 11 may be described as a U-shaped conduit. The pipe 20 is extended as at 21 beyond the header 10 and carries a T 22. A rod 23 is threaded into the T 22 and lies within the pipe 20, the rod 23 being provided with an exposed, squared end, whereby the rod may be manipulated readily. Assembled with the T 22 is an upstanding angular connection 25 controlled by a needle valve 26 and provided with an inlet nipple 27 with which is connected a fuel supply pipe 28. Any suitable means may be provided for supplying fuel to the pipe 28, a tank being used if desired. However, since a device of the type herein disclosed cannot be characterized patentably by any specific means for supplying fuel to the pipe 28, no such means has been or should be shown and described.

Coöperating with the deflector 1 and supported thereby is a cap which is denoted by the numeral 29, the cap if desired being provided with an outlet pipe 30 in its top, whereby the gas within the contour of the cap may be conducted away to a lamp burner or any other structure which it is desired to supply with gas. The cap 29 embodies a depending extension 31 fitting within the flange 4 of the deflector 1, the cap embodying an outstanding flange 32 which rests on the flange 4 of the deflector and

constitutes a means whereby the cap is supported. The outstanding flange 32 of the cap 29 is provided, beyond the flange 4 of the deflector 1, with a plurality of gas outlets 5 let openings 33.

Connected with the bottom of the cap 29 and opening thereinto is an angular air inlet 34 equipped at its sides with lugs 35 receiving slidably rods 36 assembled with a valve

10 plate 37 mounted to move toward and away from the inlet 34, so that the air supply thereto may be regulated at the will of an operator. The valve plate 37 is mounted to slide to and fro on a nozzle 38 controlled by 15 a needle valve 39, the valve plate 37 being provided with a rod 40 mounted to slide in a lug 41 formed on the side of the nozzle 38. An angular pipe 42 forms a connection between the nozzle 38 and one end of the 20 pipe 19 by way of the passage 17 in the header 10, the pipe 42 being jacketed if desired as shown at 43. Depending from the nozzle 38 is a stem 44 supporting a priming cup 45.

25 There may be used in connection with the device above described, an absorbent member 46 provided with hooks 47 adapted to engage with the pipes 19 and 20, the absorbent member being saturated with an inflammable fluid and being suspended beneath the pipes, to heat the same, when desired, the movable section 9 of the deflector 1 being turned down into a depending position. It 30 will be understood that if desired, any inflammable substance, such as wood alcohol, may be placed in the priming cup 45 and ignited, for the purpose of affording the necessary heat at the starting of the structure, at the nozzle 38.

40 In practical operation, fluid fuel is fed by way of the pipe 28 and the nipple 27 into the pipe 25, the flow of fuel being regulated by means of the valve 26. The fuel passes from the pipe 25 into the pipe 20-21. The 45 fuel thence traverses the passage 15 in the header 11 and moves through the pipe 19, the fuel being spread out around the inner wall of the pipe 20 by the action of the rod 23. From the pipe 19 the fuel which has 50 now been forced into gas, passes through the angular pipe 42 and into the nozzle 38, where the flow of gas is regulated by the valve 39. The gas is discharged into the air inlet 34, the supply of air into the inlet 55 being regulated by moving the plate or valve 37 through the instrumentality of the rod 40. The mixture of air and gas thus produced in the inlet pipe 34 passes upwardly into the cap 29 and passes out of the cap by way of 60 the openings 33 in the horizontal flange 32 of the cap. The mixture burns in the openings 33 and is deflected by the rim 2. It is to be observed in this connection that the

movable deflector section 9 may be operated by means of the rod 7, so as to deflect 65 the flame to a greater or less extent across and upon the pipes 20 and 19 it being in these pipes that the transformation of the liquid fuel into gas is brought about. If desired, as hereinbefore stated, the gas may 70 be led away from the cap 29 by the pipe 30 and be employed for any desired purpose.

Ordinarily, the device as shown in Fig. 1, is placed within a stove or heater of any desired sort to replace the fuel grate usually 75 found in such structures.

Having thus described the invention, what is claimed is:—

1. In a device of the class described, a deflector embodying a bottom and an upstanding marginal rim, a portion of the rim being movable; means for moving the movable portion of the rim; a U-shaped conduit carried by the deflector and located adjacent the movable portion of the rim; means for supplying fuel to one end of the conduit; a cap supported by the bottom of the deflector and provided with burner orifices coacting with the rim; an air inlet assembled with the cap; and means connected with the other end of the conduit for discharging gas into the air inlet.

2. In a device of the class described, a deflector provided with an upstanding marginal rim, a portion of which is cut away, the rim being provided with flanges at the cut away portion; a U-shaped fuel conduit supported on the flanges; a movable deflector section journaled in the flanges for movement toward and away from the conduit; means for supplying fuel to one end of the conduit; a cap assembled with the bottom of the deflector and provided with a burner orifice; an air inlet assembled with the cap; and means for discharging gas from the conduit into the air inlet.

3. In a device of the class described, a deflector provided with an upstanding rim having an opening; a movable deflector section carried by the rim and coöperating with the opening; a pair of headers assembled with the rim adjacent the ends of the opening; pipes connecting the headers; a rod removably inserted into one pipe; means for supplying fuel to the said pipe; a cap carried by the deflector; an air inlet assembled with the cap; and means for conducting gas from the other pipe to the air inlet.

In testimony that I claim the foregoing as my own, I have hereto affixed my signature 120 in the presence of two witnesses.

IRA C. WILLIAMS.
